UNITED STATES PATENT OFFICE.

FREDRIK LJUNGSTRÖM, OF LIDINGO-BREVIK, AND ISIDOR BROBERG, OF LIDINGON, SWEDEN, ASSIGNORS TO AKTIEBOLAGET LJUNGSTRÖMS ÅNGTURBIN, OF STOCKHOLM, SWEDEN, A CORPORATION.

AIR-COOLED CONDENSER.

Application filed April 18, 1922. Serial No. 552,413.

To all whom it may concern:

Be it known that we, FREDRIK LJUNGSTRÖM, chief engineer, and ISIDOR BROBERG, engineer, subjects of the King of Sweden, residing at, respectively, Lidingo-Brevik, Sweden, and Tallhyddan, Skarsatra, Lidingon, Sweden, have invented certain new and useful Improvements in or Relating to Air-Cooled Condensers, of which the following is a specification.

In air-cooled condensers for locomotives and similar carriages it has previously been suggested to use fans placed at the side of one another to force the cooling air. In case of large locomotives the necessary room is rather limited on account of the necessity of constructing the extended condenser as short as possible in regard of the difficulties of using long carriages in curves and on turntables. By giving the air-cooled condenser a more compact shape, it has been possible to reduce its length, in which case, however, an increased quantity of air is required to cool the same. In this case it has proved difficult to place within the reduced space the necessary number of fans.

This invention relates to the placing and driving of the fans within a reduced space and consists in that two or more of the fans are so spaced that the distance between two adjacent shafts of the fans is less than the sum of the radii of the fans mounted on said shafts. A further feature of the invention consists in that the shafts of the fans are located in the same or about the same plane and so spaced that the ranges of operation of two adjacent fans intersect one another, in which case the fans may be situated in the same or about the same plane, so that the blades of one fan pass between the blades of the other fan.

The accompanying drawings illustrate a condenser adapted for locomotives and provided in one embodiment with fans operating one above another and in the other embodiment with fans operating in the same plane.

Fig. 1 shows a side view of the first embodiment;

Fig. 2 shows a section through this first embodiment, certain parts of the condenser being omitted;

Fig. 3 shows a plan view of the fans;

Figs. 4, 5 and 6 are similar views of the second embodiment.

55

The condenser shown consists of an air-cooled part and an accumulating liquid receptacle 2 co-operating in known manner with said air-cooled part 1. The steam from the main turbine 3 enters the receptacle 2 and passes through the pipings 4 into a distributing pipe 5. From said pipe the steam passes through the cooling elements 6 of the air-cooled part 1 and returns then in the form of water of condensation 65 through the discharge pipes 7 to the liquid receptacle 2.

In this case the fans 8 and 9 are mounted above the liquid receptacle and beneath the air cooler. According to the invention the fans 8 and 9 are placed so close to each other that the distance between their axes of rotation is less than the sum of their radii r_1 and r_2 , the ranges of operation of the fans thus intersecting each other. In this embodiment the fans, in order to make their location possible, are disposed in different planes, the fans 8 being placed above the fans 9.

The fans are mounted on the pipe 5 and their driving device is situated below the supporting device. The fans are driven by the shaft 10 by means of toothed wheels 11 and rotate either in the same direction or in opposite directions. The fans operate within casings 13 and partitions 14 separating the air channels of the fans from one another. The shaft 10 is driven by a turbine 12, if desired, by the aid of a toothed gearing.

In Figs. 4, 5 and 6 showing also a condenser of the type described above, the fans are placed in the same plane, the blades of one fan, in the same manner as the teeth of a toothed wheel pass between the teeth of another toothed wheel with the difference that the blades do not contact with each other, pass between the blades of the other fan. The fans are so driven by the shaft 10 and the toothed wheels in opposite directions that every other fan rotates in the same direction. The fans are mounted on shafts situated in about the same plane and one after another in the longitudinal direction of the condenser.

90

Obviously other locations of the shafts of

105

the fans may be imagined in case the fans are situated at the side of one another or one after another in two or more rows, while the ranges of the fans intersect one another. This will be the case when the distance between two shafts is less than the sum of the radii r_1 and r_2 of the fans mounted on said shafts.

What we claim as new and desire to secure by Letters Patent of the United States is:—

- 10 1. In a blower for air-cooled condensers for locomotives and similar carriages, in combination a plurality of fans arranged at the side of each other for forcing cooling air through the air-cooled condenser, a shaft for each of said fans, said shafts being so spaced that the distance between two adjacent shafts is less than the sum of the radii of the fans mounted of said shafts, and means for dividing the flow of air into parallel streams, one stream for each of said fans.
- 15 2. In a blower for air-cooled condensers for locomotives or similar vehicles, in combination a plurality of fans arranged at

the side of each other for forcing cooling air through the air-cooled condenser, a shaft for each of said fans, said shafts being placed in approximately the same plane at such a distance from one another that the ranges of two adjacent fans intersect each other, and means for dividing the flow of air into parallel streams, one stream for each of said fans.

3. In a blower for air-cooled condensers for locomotives and similar carriages, in combination a plurality of fans arranged at the side of each other for forcing cooling air through the air-cooled condenser, a shaft for each of said fans, said shafts being so spaced that the distance between two adjacent shafts is less than the sum of the radii of the fans mounted of said shafts, and partitions for dividing the flow of air into parallel streams, one stream for each of said fans.

In testimony whereof we affix our signatures.

FREDRIK LJUNGSTRÖM.
ISIDOR BÖRBERG.
